(57) CLAIM

The ornamental design for a portable pet food container, as shown and described.

DESCRIPTION

FIG. 1 is a front perspective of a portable pet food container showing a first embodiment of our new design.

FIG. 2 is a rear perspective view thereof.

FIG. 3 is a front plan view thereof.

FIG. 4 is a rear plan view thereof.

FIG. 5 is a first side view thereof.

FIG. 6 is a second side view thereof.

FIG. 7 is a top plan view thereof.

FIG. 8 is a bottom plan view thereof.

FIG. 9 is a top perspective view of the portable pet food container of FIG. 1 attached to an exemplary wearable device.

FIG. 10 is a rear plan view thereof.

FIG. 11 is a front perspective of a portable pet food container showing a second embodiment of our new design.

FIG. 12 is a rear perspective view thereof.

FIG. 13 is a front plan view thereof.

FIG. 14 is a rear plan view thereof.

FIG. 15 is a first side view thereof.

FIG. 16 is a second side view thereof.

FIG. 17 is a top plan view thereof.

FIG. 18 is a bottom plan view thereof.

FIG. 19 is a top perspective view of the portable pet food container of FIG. 11 attached to an exemplary wearable device; and,

FIG. 20 is a rear plan view thereof.

The broken lines represent portions of the portable pet food container that form no part of the claimed design.

1 Claim, 18 Drawing Sheets
